UNITED STATES PATENT OFFICE.

CLARENCE E. BONNER AND JOHN W. MAUGHMER, OF NEW YORK, N. Y., ASSIGNEES,
BY MESNE ASSIGNMENTS, TO BONNER-CHARTER CORPORATION, OF DOVER, DELA-
WARE, A CORPORATION OF DELAWARE.

ENGINE CONSTRUCTION.

Application filed May 4, 1921. Serial No. 466,796.

This invention relates to a new and improved engine construction, and more particularly to a cylinder and cylinder head construction adapted for use in connection with internal combustion engines.

In such engines it is highly desirable that the cylinder and head be as simple in design as possible in order that it may be economically manufactured. It is also highly

desirable for efficiency in machining that the cylinder be open at both ends, since in this case the finishing tool may be supported at both ends. The cylinder being made as a simple sleeve may be readily formed either of cast iron pipe with a flange casting cut upon the end to retain it in place in the cylinder block; or it may be formed of a steel tube with the flange formed thereon in any desired manner.

The use of a readily removable element as a cylinder and one made of steel is particularly desirable in localities where dust is liable to be drawn in through the carburetor with the charge and to score the engine cylinder. For ease in dismantling or assembly of the engine it is highly desirable that the cylinder be removable from above, and to simplify this removal it is desirable that the cylinder be removable as a unit with the cylinder head. When such units are made, however, as separate elements, it is essential that the meeting surfaces and method of connection be such as to eliminate any possibility of power losses.

It is an object of the present invention to provide a cylinder construction comprising a simple tubular inner cylinder and a cylinder head adapted to be associated therewith, and connected thereto in such manner as to enable these two elements to be mounted and dismounted as a unit.

It is a further object to provide devices of this character which are simple in design and relatively inexpensive in manufacture.

Other and further objects will appear as the description proceeds.

Broadly, our invention comprises an engine consisting of a cylinder block having cylinder cavities open at the top and for each cylinder cavity a tubular inner cylinder adapted to fit therein and be guided by the block. It further includes a separate head for each cylinder adapted to engage the block and the upper end of the

cylinder. The cylinder is preferably provided with a flange at its upper end engaging the cylinder block and the cylinder head, and connecting screws are passed through the flange into the head to positively connect the two members. The cylinder head and cylinder are then connected as a unit to the cylinder block by means of bolts extending from the block through the head and nuts fitting on said bolts.

We have illustrated a preferred embodiment of our invention in the accompanying drawing, in which—

Figure 1 is a cross sectional view of the upper portion of an engine cylinder fitted with our invention; and

Figure 2 is a plan view of Figure 1.
As shown in the drawing, the cylinder block 3 is provided with the cylindrical interior opening 4, the upper ends of which are shouldered at 5. The inner cylinder 6 is fitted within the member 3 and is provided with a circumferential shoulder 7 at its upper end engaging the block. The cylinder block is further provided with the cooling liquid cavity 8 having an outlet port 9 at its upper end coaxing with an inlet port 10 in the cylinder head 11. This head 11 is provided with an outlet 12 and its central portion 13 is provided with the cylindrical extension 14 extending downwardly into the upper end of the cylinder member 6. The water jacket extends downwardly into this portion 14 and the spark plug 15 is threaded into the cap and extends through its lower portion. The cylinder head is retained in place upon the cylinder block by the bolts 16 and nuts 17. The upwardly extending screws 18 and 19 extend through the flange 7 of the cylinder and into the cylinder head 11. These screws are countersunk in the cylinder flange.

As shown in the drawing, a sleeve valve member 20 is fitted in the cavity 4 between the cylinder block and the cylinder member. It forms no part of the present invention, however, and will not be further described herein.

It will be observed that the screws connecting the cylinder and cylinder head are incapable of adjustment or removal when the cylinder and head are assembled in the cylinder block. By removal of the nuts 17 the cylinder head and cylinder member are

removed from the block as a unit. The head may then be removed from the cylinder if desired by removing the screws 18 and 19.

5 This unitary connection between the head and the cylinder affords the advantages formerly had where the cylinder and head were cast integrally; and on the other hand it gives very great advantages as to the ease 10 of casting of the head and in machining and finishing both the head and the cylinder, which latter need not be cast, but may be a drawn steel tube or otherwise formed. The advantages of the unitary structure are 15 present, since the head is closely fitted in the cylinder and due to its annular engagement therewith—an engagement on both the inner surfaces and the top flange—no danger of leakage is present. This is true, since the 20 nature of the meeting surfaces readily adapts them for accurate machining. On the other hand, as has been stated, the construction in two parts adds many advantages in manufacture.

25 A further advantage lies in the fact that one cylinder may be used interchangeably with different heads. In this way heads having different extensions into the cylinder of differing lengths may be used without further 30 change in the engine construction, thus varying the effective cylinder capacity and the compression in the engine. The engine, therefore, without further change than the substitution of different cylinder heads, may 35 be adapted for general use or with moderate compression; for slow heavy-duty use with low compression; or with a head extending well into the cylinder, it provides a high compression engine for high speed use.

40 Our construction is simple in design and may be readily manufactured and installed at relatively low cost. It is effective in operation and materially facilitates the assembly and dismantling of the engine.

45 We claim:

1. In an internal combustion engine, a cylinder block, a cylinder member removably fitted therein in such manner as to be removable from the top of the block, said cylinder member being open at the upper end,

and a cylinder head removably attached to said cylinder member to form a gas tight connection therewith.

2. In an internal combustion engine, a cylinder block, a tubular cylinder member fitted 55 therein, a cylinder head attached to the cylinder member to make a gas tight connection therewith, said cylinder member and head being adapted to be attached or removed from the cylinder block as a unit, and means 60 to detachably retain said unit in the cylinder block.

3. In an internal combustion engine, a cylinder block, a tubular cylinder member fitted 65 therein, a cylinder head attached to the cylinder member by means completely inclosed when the cylinder member and head are assembled in the block, said cylinder member and head being adapted to be attached or removed from the cylinder block as a unit, 70 and means to detachably retain said unit in the cylinder block.

4. In an internal combustion engine, a cylinder block, a tubular cylinder member fitted 75 therein, a flange upon said cylinder member, a cylinder head attached to the cylinder member flange by screws passing through the flange upwardly into the head, said cylinder member and head being adapted to be attached to or removed from the cylinder 80 block as a unit, and bolts passing through the head to retain said unit upon the cylinder block.

5. In an internal combustion engine, a cylinder block, a cylinder member adapted to 85 be associated therewith, said cylinder member being open at its upper end and adapted to have a cylinder head fitted to said upper end, said cylinder head having a portion fitting into said cylinder member any preferred distance, the cylinder head and cylinder member being detachably connected to each other whereby they may be removed as a unit from the cylinder block.
